UNITED STATES PATENT OFFICE.

GEORGE A. WIECHERT, OF NEW YORK, N. Y.

CENTRIFUGAL CASTING MACHINE.

Application filed September 28, 1922. Serial No. 591,029.

My invention relates to centrifugal casting machines of a type suitable for general use, and particularly adapted for making small and light castings, including dentures.

More particularly stated, I seek to do away entirely with the rotary casting arm heretofore used, and to make a number of distinct improvements in casting machines, for the purpose of increasing the efficiency thereof.

Reference is made to the accompanying drawing forming a part of this specification, and in which like letters indicate like parts throughout the several figures.

Figure 1 shows my improved casting machine, partly in rear elevation and partly in section.

Figure 2 is a fragmentary plan showing the molding flask and means for supporting the same upon the shaft.

Figure 3 is a side elevation of the flask.

Figure 4 is a fragmentary view, partly a side elevation and partly a section, of the mechanism appearing in Figure 1.

Figure 5 is an elevation of the sprue plate, and parts carried thereby.

Figure 6 is a longitudinal section through the flask and parts contained therein, ready to receive the investiture, and is taken upon the line 6—6 of Figure 7, looking in the direction indicated by the arrows.

Figure 7 is a plan view of the flask and the sprue plate mounted thereupon and used in connection therewith.

Figure 8 is a front elevation of the flask and sprue plate.

Figure 9 is a section on the line 9—9 of Figure 7, looking in the direction indicated by the arrows, and showing a core and other parts supported within the flask.

Figure 10 is longitudinal section through the flask and its contents, when ready for molding.

Supported by a table 10 is a casing 11, provided with a pair of lugs 12 for engaging the upper surface of the table, as shown more particularly in Figures 1 and 4. The casing is provided with a downwardly extending member 13, carrying a laterally extending portion 14. A set screw 15 extends through the portion 14, and is used for securing the casing upon the table 10. The casing is provided with bolts 16, which in this instance are four in number, and is further provided with a laterally extending portion 17 of substantially tubular form,

constituting a bearing. A revolute shaft 17^a extends through the bearing 17 and into the casing. Mounted rigidly upon the shaft 17^a is a crank arm 18, carrying a handle 19. These parts are so arranged that the operator, by grasping the handle 19 and turning the crank 18, causes the rotation of the shaft 17^a. Mounted rigidly upon the shaft 17^a and located within the casing 11 is a gear wheel 20 of rather large size, as may be understood from Figure 1. A pinion 21, located within the upper part of the casing, engages the gear wheel 20 and is turned by the rotation thereof. The casing is provided with two bearings 22 and 23, in axial alignment with each other, and each having a substantially tubular form. A revolute shaft 24 is supported by these bearings, and carries the pinion 21 whereby the shaft is driven. The ratio of the gearing, in the mechanism here shown, is 13 to 1. An oil cup 25, mounted upon the casing, is used for lubricating the pinion 21 and shaft 24.

The flask used for casting appears at 31, and carries a lug 26, provided with a small hole 27. The lug is integral with the flask, and extends laterally outward from it.

The shaft 24 is provided at its outer or free end with a slot 28, so arranged that the lug 26 may be fitted snugly into the slot, thus supporting the flask directly upon the end of the shaft. The shaft 24 is provided with a hole 29, extending axially through it and so positioned as to register with the hole 27 through the lug 26 when this lug is fitted into the slot. A cotter pin 30 extends through the holes 27 and 29, and holds the lug 26 and the shaft 24 firmly together.

A weight 32 is provided with a collar 33 integral with it, and is further provided with a set screw 33^a, whereby it is detachably mounted upon the shaft 24.

The flask is cut away at its top, reckoning from the position indicated in Figure 9, so as to form a step 31^a as shown in this figure.

A sprue plate 34 is fitted upon the flask 31, and is provided with a vertically extending portion 34^a, as indicated in Figure 6, so that the sprue plate as a whole, as seen in cross section in this figure, has a step formation. The sprue plate is provided with a notch 35 of considerable width, and with a pair of notches 36 of less width, these notches serving the general purpose of air vents. The sprue plate has a downwardly

extending tongue 37, the lower end of which is provided with a slot, adapted to hold a small quantity of wax 38 as indicated in Figure 5. The tongue 37 is rather wide, as indicated in this figure, and thus presents a flat surface adapted for holding another charge of wax 40, as shown. A saucer 39, made preferably of metal, is detachably secured upon the tongue 37 by aid of the wax 10, as indicated in Figure 5. For this purpose the saucer 39 is simply pressed against the wax. Owing to the plasticity of the wax, the saucer 39 may be moved slightly in relation to the tongue 37. This is done 15 by the operator simply pressing with his fingers upon the saucer 39, and at the same time slowly pushing the saucer edgewise. Thus the saucer can be secured by aid of the wax, in an infinite number of slightly different positions, upon the tongue 37. The saucer is detachable from the tongue 37, as it is not held thereto by anything except the wax. A core 41 may be supported upon the lower end of the tongue 37 by means of the wax 38, as may be understood from Figure 20 25 6. This core 41 may support a wax facing 42 as shown in this figure.

Wax threads 43 and 44 are connected with the filling 42 and core 41. These wax 30 threads, and the filling 42 are used as hereinafter described. The wax threads 43 extend out to the notches 36, and the wax threads 44 extend out to the notch 35.

I will next describe the manner of preparing investiture to be used in the flask 31. The sprue plate 34, carrying various parts as shown in Figure 6, is lifted upwardly from the flask 31, and the flask is then filled with a semi-liquid or plastic material capable of hardening or setting and also capable of withstanding a high temperature. For this purpose I may use either plaster of Paris or any of the various compositions suitable for use in preparing flask molds. While 35 the material is still soft the sprue plate 34 is gently lowered and rested upon the top of the flask, so that the tongue 37, the saucer 39, the core 41 and other parts are submerged within the filling, which extends entirely to the top of the flask and which, because of the shape of the sprue plate, now has a step formation. The filling is next allowed to set and thus to harden. This done, the flask 40 and its contents are subjected to a moderate heating for some little time. This heating melts and dries out all of the wax, wherever located, within the flask. Next the sprue plate 34 is lifted and removed, carrying with it of course the tongue 37, but leaving behind it the saucer 39, the saucer being now freed from the tongue by the disappearance of the wax. The operator next removes the saucer 39. This leaves the flask and its contents in the condition indicated in Figure 10. The filling is shown at 45, the core 41 now being

partially embedded within it. A cavity 46 partially bounds the filling 41, occupying the position previously occupied by the wax facing 42 and shown in Figure 6. Air passages 47 and 48 communicate with the filling 41, 70 and occupying positions previously occupied by the wax threads 43 and 44. These air passages lead to the notches 35 and 36.

The flask and its contents as shown in Figure 10 being now ready for molding, the 75 flask is placed in position upon the machine in the manner above described. The handle 19 has previously been turned into such position that the flask, when thus in position upon the machine, extends obliquely downward from the shaft 24, as indicated in Figure 1. Next a charge of gold or other metal to be used in casting is placed within the cavity 49, and is then heated, by a blow pipe or in any other appropriate manner, until 80 melted and of the proper temperature for casting.

This done, the operator turns the handle 19, so that the shaft 24 begins its rotation instantly, and the molten metal is by centrifugal force driven outwardly and thus toward the bottom of the flask, the air contained within the flask making its escape through the passages 47 and 48. Finally the filling 46 is removed and broken, the finished casting, corresponding to the cavity 46, being thus recovered.

In the construction above described I do not use any crucible, as none is necessary. The melting of the metal used in casting, 100 the flow of this metal after it is melted, and its hardening after being formed into the casing, are steps all of which take place altogether within the body of the flask.

It will be noted that the distance from the 105 shaft 24 to the outer or bottom end of the flask is shorter than the length of the flask. In fact the flask is partially cut away in order to accommodate the shaft 24, as may be understood from Figures 1 and 2. Such 110 being the case, the flask may be considered as extending directly outward from the shaft; or to state the matter in another way, the flask, reckoning from its outer or bottom end, reaches inwardly beyond the center of 115 the shaft. Thus I use no casting arm whatever, or any equivalent for a casting arm.

The expulsion of the air from the mold is by this arrangement quite effective, in that the air by traveling radially inward toward the center of rotation of the flask, has a number of unobstructed paths. The molten metal, forced outwardly by centrifugal force, displaces the air in the mold, and thus drives the same inwardly or toward the center of 120 rotation, the air thus being discharged inwardly as regards the center of rotation.

As all parts of the machine are preferably made small and light, the ratio of the gearing may be relatively high. While in this 125

particular instance the ratio is 13 to 1, any other suitable ratio may be employed. I find that with the ratio of 13 to 1, and with the various revoluble parts made light and small, a relatively high speed of rotation may be instantly conferred upon the flask, so that there is no possibility of the molten metal traveling in the wrong direction due to any lag in speeding up the flask. The operator turns the handle in a clockwise direction and the flask rotates in the opposite direction, so that the molten metal has no chance to spill out of the flask.

My machine is well adapted for small castings of many kinds, including dentures and many forms of jewelry.

I do not limit myself to the precise mechanism shown, as variations may be made therein without departing from the spirit of my invention.

Having thus described my invention what I claim as new, I desire to secure by Letters Patent is as follows:

1. In a molding apparatus the combination of a sprue plate provided with a portion for extending into a flask, and a member separate from said portion and detachably carried thereby, for the purpose of forming an impression in an investiture to be carried by the flask.

2. A device of the character described comprising a flask and a sprue plate fitted thereto, said sprue plate being provided with a tongue so positioned as to extend into the flask when the sprue plate is in position thereupon, and a member detachably mounted upon said tongue and having the proximate form of a saucer.

3. A device of the character described comprising a flask and a sprue plate fitted thereto, said sprue plate being provided with a portion extending to the flask when the sprue plate is in position upon the flask, means for supporting a core upon said portion thus extending into the flask, and a member mounted upon said portion and movable relatively thereto, for the purpose of making an impression upon a filling within the flask.

4. As an article of manufacture, a sprue plate provided with an extending portion and with means for detachably supporting upon said extending portion a core to be disconnected therefrom, and means for holding said member upon said portion, so as to allow said member to be shifted slightly in position relatively to said extending portion,

for the purpose of affecting the form of an investiture within said flask.

5. The combination of a flask and a filling contained therein, said filling containing a core and a cavity partially bounding said core in order to form a casting connected with the core, said filling also containing a cavity communicating with first mentioned cavity for the purpose of holding a quantity of metal while the same is being melted in order to form a casting.

6. The combination of a flask and a filling contained therein, said filling being provided with a cavity for forming a casting and with an air passage for venting said cavity as the latter is filled with molten metal, said filling being also provided with a cavity communicating with said first-mentioned cavity for the purpose of holding a quantity of metal while the same is being melted.

7. The combination of a flask and a filling carried thereby, said filling being provided with a cavity in which the casting is to be formed and further provided with a core partially bounding said cavity, and with air passages communicating with said core and said core and said cavity, said filling being also provided with a portion formed into a cavity for supporting a quantity of metal while the same is being melted, and before it is discharged into first mentioned cavity.

8. In a device of the character described a sprue plate provided with a tongue, a quantity of wax adhering to said tongue, and an impression member adhering to said wax.

9. In a device of the character described a sprue plate provided with an extending portion, and a member carried by said sprue plate for the purpose of affecting the form of a mold to be made by aid of the sprue plate, and means for enabling the operator to shift the position of said member relative to said extending portion in order to vary the form of said mold.

10. In a device of the character described the combination of a flask and a sprue plate mounted thereupon, said sprue plate being provided with a tongue extending into said flask and further provided with a slot extending into said tongue for the purpose of carrying a small quantity of wax.

11. A device of the character described comprising a flask and a sprue plate fitted thereto, said flask and sprue plate having together a step formation.

GEORGE A. WIECHERT.
